CLAIM

The ornamental design for a set of ergonomic adjusters, as shown and described.

DESCRIPTION

FIGS. 1 and 8, taken together, are a front perspective view of my new design for a set of ergonomic adjusters.

FIGS. 2 and 9, taken together, are a front side elevation view of FIGS. 1 and 8.

FIGS. 3 and 10, taken together, are a left side elevation view of FIGS. 1 and 8.

FIGS. 4 and 11, taken together, are a back side elevation view of FIGS. 1 and 8.

FIGS. 5 and 12, taken together, are a right side elevation view of FIGS. 1 and 8.

FIGS. 6 and 13, taken together, are a top side plan view of FIGS. 1 and 8; and,

FIGS. 7 and 14, taken together, are a bottom side plan view of FIGS. 1 and 8.
